UNITED STATES PATENT OFFICE.

GEORGE D. BISHOP AND CLARENCE P. HARTMAN, OF CARLISLE, PENNSYLVANIA.

MOLDER'S FLASK.

Application filed April 29, 1924. Serial No. 709,821.

To all whom it may concern:

Be it known that we, GEORGE D. BISHOP and CLARENCE P. HARTMAN, citizens of the United States, residing at Carlisle, in the county of Cumberland and State of Pennsylvania, have invented certain new and useful Improvements in a Molder's Flask, of which the following is a specification.

This invention relates to new and useful improvements in molders' flasks of the snap flask type and has for its principal object to provide a means whereby the sections comprising the flask may be adjusted with respect to each other to suit different sizes of patterns, thereby obviating the necessity of having to employ a separate flask for each different size.

One of the important objects of the present invention is to provide a molder's flask of the above mentioned character, wherein a connection between the drag and the cope provides an intermediate section when in an extended position for increasing the depth of the flask to receive a similar size pattern.

A still further object of the present invention is to provide a molder's flask of the above mentioned character, wherein means is associated with the same for holding the drag and cope and the collapsible extension hingedly connected therebetween may be held in an extended position against accidental collapsing when in use.

A further object of the present invention is to provide a molder's flask of the above mentioned character, which is simple in construction, inexpensive, strong and durable and furthermore adapted for the purposes for which it is designated.

Other objects and advantages of this invention will become apparent during the course of the following description.

In the accompanying drawings forming a part of this specification and in which like numerals designate like parts throughout the same:

Figure 1 is a side elevation of our improved molder's flask showing the same in an extended position.

Figure 2 is a top plan view thereof.

Figure 3 is a sectional view taken approximately on line 3—3 of Figure 2.

Figure 4 is a fragmentary sectional view of the hinged jaws between the plates comprising the intermediate section.

Figure 5 is a fragmentary detail perspec-

tive view of one of the locking members with the actuating means associated therewith, and

Figure 6 is a detail perspective view of one of the supporting brackets.

In the drawings wherein for the purpose of illustration is shown the preferred embodiment of our invention, the numeral 1 designates the drag, and the cope is designated by the numeral 2. For the purpose of convenience, the drag may be termed as the lower section while the cope may be termed the upper section. Each of the sections comprises two L-shaped members which are hinged together at one corner as shown at 3, 60 the opposite corner provided with clamping means shown at 4. This construction is well known in the art and a further detailed description of the same is not thought necessary. This type of construction also forms 65 what is known in the art as a snap flask. When the L-shaped members are in locked engagement with each other a substantially rectangular shaped frame is provided by each of the sections in the manner clearly 70 shown in Figure 2 of the drawings.

For the purpose of increasing the depth of the flask so as to obviate the necessity of having to employ two separate flasks of different sizes, we provide the collapsible intermediate section designated generally by the numeral 5. The intermediate section consists of hinged plates 6 and 7 respectively which are of a predetermined width and the same are hinged as shown at 8. For 75 the purpose of limiting the swinging movement of the plates in one direction we provide the stop members shown at 9 and the construction of which is more clearly illustrated in Figure 4 of the drawings. These 80 plates comprising the intermediate section are arranged on each of the sides of the upper and lower sections and is further disposed between the same in such a manner as to space the cope 2 from the drag 1 when 85 the intermediate section is in an extended position in the manner clearly shown in Figures 1 and 3 of the drawings.

The upper plate 5 is hinged at its upper end as shown at 10 to the plate 11 which extends around the bottom of the upper rectangular frame while the lower plate 7 is hinged at 12 to a similar plate 13 which extends around the top of the lower rectangular frame 1. This construction is also more 90 95 100 105 110

clearly illustrated in Figure 3 of the drawings.

This construction enables the plates 5 and 6 comprising the intermediate section and 5 which extend around the sides between the cope and drag to be folded so that the cope may lie substantially flush with the upper face of the drag whereby a flask of a smaller depth is formed.

10 When it is desired to increase the depth of the flask, the plates 5 and 6 which comprise the intermediate section are extended into the position as shown in Figure 3 whereby the cope is spaced from the drag and the 15 depth of the flask is increased according to the predetermined size of the pattern. For the purpose of preventing the accidental collapsing of the intermediate section when the same is in an extended position, we provide 20 a manually actuated locking means, the construction of which will be presently described.

The locking means comprises a plurality of vertical rods such as are shown at 14 and 25 any number of these rods may be arranged on each side of the flask in the manner as shown more clearly in Figures 1 and 2 of the drawings. The vertical rods are adapted to be supported at their lower ends in 30 suitable brackets as shown at 15 which are secured to the sides of the drag or lower section 1 at spaced intervals and the upper ends of the rods extend through aligning brackets such as are shown at 16 and which 35 are supported on the sides of the cope or upper section 2 in the manner shown in the drawings. The intermediate portions of the 40 sections of the rods are provided with the lateral fingers or projections shown at 17 and which the purpose thereof will be presently more 45 fully described. The upper ends of the vertical rods are provided with crank portions 18 and the free ends of the crank portions are connected together by means of an elongated lever or actuating member 19.

As more clearly shown in the drawings, with reference more particularly to Figure 2, each side of the flask is provided with substantially a plurality of vertical rods and 50 projecting fingers and which are adapted to be actuated by means of the elongated lever 19 and the cranks 18. It is of course to be understood that the rods and the fingers carried thereby on each of the sides of the 55 flask are operated independently of the other side.

When the plate sections comprising the intermediate or collapsible section 5 is in an extended position, the levers 19 are actuated 60 so as to cause the vertical rods 14 to have the fingers 17 carried thereby to extend inwardly between the upper and lower sections and to further have the ends of the fingers in engagement with the hinged connection 8 of the plates 6 and 7 whereby the

latter are prevented from accidentally collapsing when the flask is in an extended position.

When it is desired to use a flask of a smaller depth so as to cause the cope 2 to lie 70 substantially flush with the upper surface of the drag 1, the levers 19 are actuated in the reverse direction so as to cause the rods 14 and the fingers carried thereby to be brought out of engagement with the intermediate section and to further be disposed outwardly from between the cope and drag whereby the intermediate section may be collapsed and the cope adapted to fit over a collapsed intermediate section and resting on 80 the upper surface of the drag 1, in the manner as is obvious from the construction shown in the drawings.

It will thus be seen from the foregoing description, that a molder's flask has been 85 provided which may be readily and easily extended to another size according to the depth necessary to suit the pattern and a manually actuated locking means will hold 90 the flask in its extended position against 95 accidental collapsing when in use.

The simplicity in which our device is constructed enables the same to be manufactured at a very low cost and the parts 95 will be further strong and durable.

While we have shown the preferred embodiment of our invention, it is to be understood that various changes in the size, shape and arrangement of parts may be resorted to without departing from the spirit of the 100 invention and the scope of the appended claims.

Having thus described our invention, what we claim is:

1. A molder's flask comprising upper and 105 lower sections, an intermediate collapsible section hingedly connected thereto, and means for holding the intermediate section in an extended position whereby the upper section is spaced from the lower section. 110

2. A molder's flask comprising a drag, a 115 cope, and a collapsible section interposed between the drag and cope and hingedly connected respectively thereto.

3. A molder's flask comprising a drag, a 120 cope, a collapsible section interposed between the drag and cope and hingedly connected respectively thereto, and means for holding the collapsible section in an extended position.

4. A molder's flask comprising a drag, a 125 cope, a collapsible section interposed between the drag and cope and hingedly connected thereto, said collapsible section comprising hinged plates.

5. A molder's flask comprising a drag, a 130 cope, a collapsible section interposed between the drag and cope and hingedly connected thereto, said collapsible section comprising hinged plates, and means for en-

- gagement with the hinged plates for holding the same in an extended position whereby the cope is spaced from the drag.
6. A molder's flask comprising a drag, a cope, a collapsible section interposed between the drag and cope and hingedly connected thereto, said collapsible section comprising hinged plates, and means for engagement with the hinged plates for holding the same in an extended position whereby the cope is spaced from the drag, said means comprising vertical rods journaled on the sides of the cope and drag, supporting brackets therefor, projecting fingers carried by the intermediate portions of said rods adapted for engagement with the hinged plate, and means for moving the projecting fingers into an operative or inoperative position.
- 10 7. A molder's flask comprising a drag, a cope, a collapsible section interposed between the drag and cope and hingedly con-

nected thereto, said collapsible section comprising hinged plates, and means for engagement with the hinged plates for holding the same in an extended position whereby the cope is spaced from the drag, said means comprising vertical rods journaled on the sides of the cope and drag, supporting brackets therefor, projecting fingers carried 25 by the intermediate portions of said rods adapted for engagement with the hinged plate, means for moving the projecting fingers into an operative or inoperative position, said last mentioned means comprising 30 cranks mounted on the upper ends of said rods, and an operating lever secured to the opposite ends of said cranks on each of the sides of the flask.

In testimony whereof we affix our signatures.

GEORGE D. BISHOP.
CLARENCE P. HARTMAN.
